UNITED STATES PATENT OFFICE

151,968

DESIGN FOR A CABINET FOR SHOE SHINING MACHINES

Carl E. Danielson, North Sacramento, Calif.

Application April 16, 1948, Serial No. 145,768

Term of patent 14 years

(Cl. D9—2)

To all whom it may concern:

Be it known that I, Carl E. Danielson, a citizen of the United States, residing at North Sacramento, in the county of Sacramento and State of California, have invented a new, original, and ornamental Design for Cabinet for Shoe Shining Machines, of which the following is a specification, reference being had to the accompanying drawing, forming a part thereof.

Figure 1 is a front perspective view of a cabinet for shoe shining machines, looking toward one side thereof, and showing my new design.

Figure 2 is a side elevational view of the cabinet for shoe shining machines on a reduced scale; the opposite side of the cabinet presenting the same appearance.

The dominant features of my design reside in those portions shown in full lines.

I claim:

The ornamental design for a cabinet for shoe shining machines, as shown and described.

CARL E. DANIELSON.
